UNITED STATES PATENT OFFICE.

HENRY IZARD, OF PORTLAND, OREGON.

OIL-GAS GENERATOR.

1,263,772.

Specification of Letters Patent. Patented Apr. 23, 1918.

Application filed August 2, 1917. Serial No. 184,114.

To all whom it may concern:

Be it known that I, HENRY IZARD, a citizen of the United States, residing at Portland, in the county of Multnomah and State of Oregon, have invented certain new and useful Improvements in Oil-Gas Generators; and I do declare the following to be a full, clear, and exact description of the invention, such as will enable others skilled in the art to which it appertains to make and use the same.

My invention relates to oil gas generators and more particularly to that class of generators designed to be used with the heavier and substantially non-volatile fuel oils.

The principal object of my invention is to provide a generator of this character in which the fuel oil is first vaporized and then further heated to form a gas which gas is discharged in a suitable manner and ignited to form the burner flame.

Another object of my invention is to provide a generator of this character which is so constructed that the flame will be directed most advantageously against all parts of the generator in order to insure an efficient operation of the same.

A further object of my invention is to provide with a generator of this character, a priming pan which is so constructed as to support a generator and which is provided with means whereby a continuous flame is maintained beneath the generator so that should the flame issuing from the generator become suddenly extinguished, any gases would be instantly ignited by the flame in the priming receptacle, thereby insuring a means for preventing any explosion of the accumulated fuel gases.

A further object of my invention is to provide a priming pan as described with which means are provided for flooding the pan so that raw oil may be burned in the priming pan in order to pre-heat the generator and may also be burned during the operation of the generator to insure the application of a greater degree of heat to the same.

To this end, my invention resides in the novel construction, combination and arrangement of parts to be more fully described and claimed and taken in connection with the accompanying drawings which form a part of this application and in which:

Figure 1 is an elevation of my improved generator in assembled relation;

Fig. 2 is an elevation from another point of view thereof;

Fig. 3 is a vertical section through the line 3—3 of Fig. 2;

Fig. 4 is a top plan view of the generator;

Fig. 5 is a horizontal section on the line 5—5 of Fig. 1;

Fig. 6 is a similar section on the line 6—6 of Fig. 1; and

Fig. 7 is a similar section on the line 7—7 of Fig. 1.

Fig. 8 is a horizontal section on the line 8—8 of Fig. 3.

Referring to the drawings in describing my invention in detail, it will be seen that my improved generator comprises a priming pan or receptacle 1 which is adapted to be suitably secured on a base in any desired manner and is constructed to act as a support for a generator 2 supported thereon.

The priming pan or receptacle comprises an annular pan having a relatively large centrally located vertically extending bore therethrough and provided at the top of its inner edge 3 with a series of spaced upstanding lugs 4. Depending from the bottom of the priming pan is a pipe or conduit 5 having a communication with a supply reservoir 6 located therebelow, which reservoir is adapted for connection with a fuel supply tank.

Extending through the conduit 5 is a wick 7 in communication with the fuel stored in the reservoir 6 so as to provide a means whereby a continual flame or pilot light may be maintained in the priming pan.

Extending from the reservoir 6 and connected to any suitable supply tank is a connecting pipe 8 provided with a control valve 95 therein whereby the wick in the conduit 5 may be flooded to permit of the discharge of the raw fuel oil into the priming pan.

The generator 2 is provided with a circular base chamber 9 of less diameter than the diameter of the annular priming pan and which is adapted to be supported on the upstanding lugs 4 of the priming pan and is provided with a flat bottom 10 so that it may rest securely upon the same and in spaced relation thereabove. The base chamber 9 is provided with a flat top 11 and in communication with the upper circular

chamber 12 by means of a pair of oppositely disposed upwardly extending pipes 13 extending upwardly from the opposite sides of the base chamber and supporting the upper chamber. The upper chamber 12 is of greater capacity than the base chamber 9 but is of the same diameter as the chamber 9 and is provided with a centrally located vertically extending bore 14 therein for a purpose to be hereinafter described. Connected at its ends to diametrically opposed points at the sides of the top of the upper chamber 12 is a diametrically extending pipe 15 which is arched throughout its length to be disposed in spaced relation above the top of the upper chamber 12 and which extends over the bore 14. The under side of the pipe 15 is provided with a discharge aperture 16 disposed in direct vertical alinement with the bore 14 located in the chamber 12.

Extending from a suitable fuel supply tank upwardly through the centrally located bore in the priming pan is a fuel supply conduit 17 having communication with a fuel passage 18 in the bottom of the base chamber 9 of the generator.

In the operation of my device, the priming pan or receptacle is first provided with a suitable quantity of raw fuel oil by means of the flooding of the wick disposed in the conduit 5 after which the oil is ignited and will burn to pre-heat the generator, the flame from the burning oil ascending along the sides of the generator chamber owing to the greater diameter of the annular priming receptacle which will dispose the outer edges of the priming receptacle beyond the outer side edges of the generating chambers. When the oil contained in the priming receptacle has been burned out, oil will be fed through the wick 7 which will burn and provide a continuous flame below the burner which I designate as a pilot light. If at any time the flame from the generator should become extinguished, this pilot light would ignite any gases which would collect and thereby prevent any explosion. If at any time during the operation of the generator, it is desired to increase the heat or the intensity of the flame, it is merely necessary to open the control valve provided in the connection 8 leading to the reservoir 6, whereby the pilot light will be flooded and raw oil will be discharged into the priming receptacle and will burn in connection with the flame from the gases generated in the burner.

When the chambers of the generator have been sufficiently pre-heated, fuel oil is allowed to enter through the passage 18 to the base chamber where it becomes vaporized and ascends through the connecting pipes 13 to the larger upper chamber 12 and in which it will expand and become gasified,

continuing to ascend upwardly and passing through the arched pipe 15 of the generator. From this pipe the generated gas will discharge with considerable force downwardly through the aperture 16 located therein and downwardly through the bore located in the upper chamber and be directed against the flat top of the base chamber where it will be caused to spread out and when properly ignited, the gases will burn at this point and mingle with the air through the air ducts formed between the upstanding lugs 4 on the priming receptacle. The flame will thus be disposed against the base chamber, against the upper chamber 80 and in fact against all parts of the generator so that the entire surface of the generator will be directly and positively affected by action of the flame to provide an efficient manner of heating the generator walls, 85 whereby to insure practically instantaneous generation not of vaporized oil but of fuel gas.

I claim:—

1. A generator as described comprising a 90 base chamber adapted for connection with a fuel supply, an upper chamber spaced above said base chamber, an upwardly extending communicating pipe securing the upper chamber to said base chamber, said 95 upper chamber having a bore extending therethrough and a pipe extending across said bore and in communication with said upper chamber, said pipe having an aperture therein in alinement with said bore to 100 discharge fuel gases downwardly through said bore.

2. A generator as described comprising a base chamber adapted for connection with a fuel supply, spaced upwardly extending 105 pipes on said chamber, a second chamber in communication therewith on the upper ends of said pipes, said second chamber having a vertically extending centrally located bore therethrough and an arched pipe over 110 the top of said second chamber having its ends in communication therewith, said arched pipe extending above the bore in said second chamber and having an outlet therein disposed in alinement with said bore to 115 discharge fuel gases downwardly through the bore.

3. A device of the character described comprising an annular priming receptacle provided with a bore extending therethrough, a series of spaced lugs on the inner edge of said receptacle, a fuel supply connection to said receptacle, a generator having a flat bottom to rest on said lugs to form air passages between said bottom and 125 inner edge of the receptacle, the outer edge of said receptacle extending beyond the side edges of said generator, and a fuel supply conduit for said generator extending upwardly through the bore in the receptacle. 130

4. A device of the character described comprising a priming receptacle, a suitable fuel supply, a generator disposed over and spaced from said priming receptacle, a connection between said generator and said fuel supply, a wick-fed burner in said receptacle providing a continuous flame, a reservoir disposed below said priming receptacle, the lower end of said wick extending into said reservoir, a fuel supply connected to said reservoir and means to control said last

mentioned fuel supply to flood said reservoir whereby to discharge fuel into the priming receptacle.

In testimony whereof I have hereunto set 15 my hand in the presence of two subscribing witnesses.

HENRY IZARD.
